UNITED STATES PATENT OFFICE.

WILLIAM E. STEVENS, OF NEW HAVEN, CONNECTICUT, ASSIGNOR TO
SARGENT & CO., OF SAME PLACE.

DESIGN FOR A COFFIN-PLATE.

SPECIFICATION forming part of Design No. 16,577, dated March 16, 1886.

Application filed January 18, 1886. Serial No. 189,018. Term of patent 14 years.

To all whom it may concern:

Be it known that I, WM. E. STEVENS, of New Haven, in the county of New Haven and State of Connecticut, have invented a new Design for a Coffin-Plate; and I do hereby declare the following, when taken in connection with accompanying drawings and the letters of reference marked thereon, to be a full, clear, and exact description of the same, and which said drawings constitute part of this specification, and represent, in—

Figure 1, a face view; Fig. 2, a transverse central section; Fig. 3, a longitudinal central section.

This invention relates to a design for the plate adapted to be placed upon a coffin, and upon which the inscription is engraved; and the design consists in the configuration, as shown in the accompanying illustration, and hereinafter described. The body of the plate is in the form of a parallelogram, the surface from side to side convex in transverse section, as seen in Fig. 2. The ends are inclined backward and downward, and the plate rests upon a flat base, as shown, the base forming a projecting border around the edge of this pecu-

liarly-shaped plate. On the two ends of the base central ornaments project in the same plane as the base, and as shown in the accompanying illustration.

30

I claim—

1. In a design for coffin-plate, consisting in an outline in the form of a parallelogram, the surface curved outward from side to side in convex shape in transverse section, the two ends inclined downward and backward to the edge and resting upon a flat base, which forms a border around the plate, as shown in the accompanying illustration.

2. In a design for coffin-plate, consisting in an outline in the form of a parallelogram, the surface curved outward from side to side in convex shape in transverse section, the two ends inclined downward and backward to the edge and resting upon a flat base, which forms a border around the plate with a projecting ornament from the sides and ends of the base, as shown in the accompanying illustration.
